UNITED STATES PATENT OFFICE.

SIDNEY SMITH, OF DETROIT, MICHIGAN.

COASTER-BRAKE.

1,104,453.

Specification of Letters Patent.

Patented July 21, 1914.

Application filed October 10, 1913. Serial No. 794,377.

To all whom it may concern.

Be it known that I, SIDNEY SMITH, a British subject, residing at Detroit, county of Wayne, State of Michigan, have invented a certain new and useful Improvement in Coaster-Brakes, and declare the following to be a full, clear, and exact description of the same, such as will enable others skilled in the art to which it pertains to make and use the same, reference being had to the accompanying drawings, which form a part of this specification.

My invention relates to an improvement in coaster brakes, shown in the accompanying drawings and more particularly pointed out in the following specification and claims.

One of the objects of my invention is to simplify the general construction of the device thereby affording a corresponding reduction in the cost of manufacture.

Another feature of the invention is to provide a relatively large braking surface while reducing the general dimension of the device, through the use of driving cams adapted and arranged to provide adequate strength and stability.

Another feature is to insure a more positive driving relation between the parts directly actuated by the driving sprocket and the co-acting elements governing the rotation of the wheel hub.

Another feature is the ease with which the parts may be replaced when required.

Other advantages and improvements will hereafter appear.

In the drawings accompanying this specification:—Figure 1 is a longitudinal sectional view of the device mounted in its bearings in the rear forks of a bicycle or motorcycle, indicating the relative position of the parts when coasting. Fig. 2 is a cross-sectional view on line 2—2 of Fig. 1, looking in the direction of the arrow. Fig. 3 is a cross-sectional view on line 3—3 of Fig. 1. Fig. 4 is a longitudinal sectional view of a fragmentary portion of the device, indicating the position of the parts when driving the wheel. Fig. 5 is an elevation (with parts broken away and in section) of the several elements constituting the brake grouped to indicate in a general way their co-acting relation. Fig. 6 is a perspective view of one portion of the co-acting annular cam provided with a ratchet face. Fig. 7 is a per-

spective view of the spring collar. Fig. 8 is a perspective view of the sleeve cam. Fig. 9 is a fragmentary perspective view of the inwardly extending hub of the driving sprocket.

Referring to the letters of reference placed upon the drawings:—A indicates the rear axle of the bicycle or motorcycle. B, B, the members of the rear fork in which the axle is non-rotatably supported.

C denotes the driving sprocket; D an inwardly extending hub threaded to receive the sprocket wheel C, the latter being held against displacement between the annular collars c and c'.

E denotes a ball bearing in the end of the hub D, and E' a ball race collar screwed to the axle A.

A' indicates a nut threaded on the axle A bearing against a washer a in turn engaging the depending bifurcated portion of the fork B.

F indicates the wheel hub. G an annular ring loosely sleeved upon the hub of the sprocket wheel C having a ratchet face g and projecting lugs g' extending into depressions f in the wheel hub that they may be rotated together.

H indicates a ball bearing housed within the ball race formed in the sprocket wheel hub, ring G, and the wheel hub.

I denotes an annular ring loosely sleeved on the sprocket hub D having on one side a ratchet face i co-acting with the ratchet face g of the ring G, its opposite side being provided with a cam face i'.

J indicates a collar having a screw-threaded engagement with the sprocket wheel hub D, secured against displacement by the annular locking ring or nut J'. The collar J is provided with a cam face j co-acting with the cam face i' of the ring I.

K denotes a sleeve rotatable on the axle A, provided with a plurality of cams k, and recessed at one end to receive the projecting tongue D' of the sprocket wheel hub D, whereby it may be revolved through the rotation of the sprocket wheel.

L denotes a split spring sleeve surrounding the cam sleeve K, adapted to bear against the inner face of the wheel hub.

K', K'', K''' indicate rolls lodged between the cam sleeve K and the spring sleeve L.

M denotes a spring collar secured against

rotation by suitable detents m to the spring sleeve L , and overlapping the collar J (being slightly dished to conform to the shape of the latter) and extending onto and into a 5 recess i^2 in the annular ring I . To increase the resiliency of the collar it is divided as indicated at m' to afford a yielding edge bearing upon the ring I .

N is a ball race collar screwed on the end 10 of the axle provided with a ratchet face n , between which and the washer a' of the nut A^2 , is clamped the depending members of the bifurcated fork B . Extending inwardly from the ball race collar N are tongues n' , 15 entering recesses l provided for their reception in the spring sleeve L to secure the latter against rotation.

O indicates a ball bearing housed between the ball race of the collar N and the race 20 in the wheel hub F .

Having indicated the several parts by reference letters, its construction will be readily understood and its operation will now be explained.

25 Upon giving the sprocket wheel C a forward impulse by "pedaling" in the usual manner, its hub D carrying the annular collar J forces the annular ring I to the right, the ratchet face of which engages the co- 30 acting ratchet face of the annular ring G engaged to the wheel hub through the lugs g' . The annular ring I is held against rotation by the dished spring collar M in order to insure it being forced into engagement 35 with the ring G through the rotation of the annular collar J .

When it is desired to coast, the rider ceases to "pedal" whereupon the wheel hub 40 rotating more rapidly than the hub of the sprocket, the annular ring I is forced out of its engagement with the ring G , through the relative difference in speed between the ratchet face g of the ring G , and the ratchet face i of the ring I , thereby causing the 45 ratchet faces of the respective rings to ride up upon those of the opposing ratchet forcing them apart;—the dished spring collar M serving to secure the annular ring against rotation and in abutting relation with the 50 collar J , as indicated in Fig. 1.

The braking action is obtained in the usual manner by "back pedaling". The hub D of the sprocket wheel upon being rotated in a reverse manner to that just described, reverses the rotation of the cam K connected with the sprocket wheel hub by the tongue D' , projecting from the end of the latter, thereby causing the rolls K' , K^2 , K^3 , to ride up the helical cams k of the 55 sleeve expanding the spring sleeve L into frictional contact with the wheel hub providing a braking action upon the wheel.

By making the element G —which is locked to the wheel hub F by the lugs g' — 60 removable, a great saving is effected in the

cost of manufacture, as it may be more readily machined while the parts are easily assembled. This also applies to the element J , screwed upon the hub of the sprocket wheel. In fact, as previously indicated, it 70 is the object of the present invention to construct the several parts so that the cost of manufacture may be reduced and the efficiency of the device correspondingly increased.

Having thus described my invention, what I claim is:—

1. In a coaster brake, a stationary axle, a sprocket wheel, a hub for said sprocket wheel, a collar having a cam face carried by the sprocket wheel hub and rotatable therewith, an annular ring free to rotate on the hub provided with a cam face adapted to be actuated by the cam face of the collar and having on its opposite side a 80 ratchet face, yieldable means to secure the annular ring against rotation with the hub when being actuated by the cam, a wheel hub sleeved over the sprocket wheel hub, and an annular ring free to turn upon the 85 sprocket wheel hub and adapted to rotate with said wheel hub having a ratchet face to co-act with the ratchet face of the annular ring.

2. In a coaster brake, a stationary axle, a 90 sprocket wheel, a hub for the sprocket wheel free to turn upon the axle, a detachable collar secured to the sprocket wheel hub having a cam face, an annular ring free to rotate on said hub provided with a cam face 95 adapted to be actuated by the co-acting cam face of the collar, having on its opposite side a ratchet face, yieldable means to hold the annular ring against rotation with the hub when actuated by the cam, a wheel hub 100 sleeved over the sprocket wheel hub, and an annular ring free to turn upon the sprocket wheel hub engaged to the wheel hub, and having a ratchet face to co-act with the ratchet face of the first named 105 annular ring, whereby the wheel hub may turn with the sprocket wheel hub.

3. In a coaster brake, a stationary axle, a sprocket wheel, a hub carrying said sprocket wheel, a collar having a cam face carried by 110 the sprocket wheel hub and rotatable therewith, an annular ring loosely sleeved on the hub provided with a cam face adapted to be actuated by the cam face of the collar, having on its opposite side a ratchet face, 115 an annular ring free to turn upon the sprocket wheel hub and engaged to the wheel hub having a ratchet face to co-act with the ratchet face of the annular ring, a sleeve provided with a plurality of cams loosely 120 mounted on the axle engaging the sprocket wheel hub that it may be rotated thereby, an expandible spring sleeve inclosing said cam sleeve and housed within the wheel hub, means to secure said sleeve against rotation, 125 130

a plurality of rolls co-acting with said cam to expand said sleeve into braking relation with the wheel hub, and a spring collar secured to said sleeve adapted to overlap the 5 collar having a cam face carried by the sprocket wheel hub and to engage the annular ring, whereby said annular ring is held against rotation and in abutting rela-

tion with the cam face collar that it may be actuated thereby.

In testimony whereof, I sign this specification in the presence of two witnesses.

SIDNEY SMITH.
